UNITED STATES PATENT OFFICE.

WOOLRIDGE B. MORTON, OF NEW YORK, N. Y.

RAILWAY CAR.

Application filed July 16, 1927. Serial No. 206,294.

This invention relates to railway cars, and has for its object to provide a sleeping car of the compartment type wherein the number of separate compartments in a car of standard size is materially increased without substantial reduction in the usable space in each compartment.

A further object of the invention is to provide a combined compartment and parlor car wherein a greater number of compartments are provided than in compartment cars as at present constructed, and at the same time sufficient additional space is obtained to provide a parlor or club compartment having at least one chair for each of the sleeping compartments.

Compartment sleeping cars as at present employed on American railroads are of two types. In the older and more usual type the compartments each contain an ordinary Pullman section consisting of upper and lower berths extending lengthwise of the car along one side. These compartments accommodate two passengers and the capacity of the car is but slightly greater than half that of the ordinary Pullman car with sections on each side of a central aisle.

In the more recent type of compartment car the rooms extend crosswise of the car and there is but a single bed or berth provided for each compartment. In such cars fourteen compartments are possible.

The car constituting the subject-matter of this application is an improvement on the later type of compartment car with the rooms extending crosswise of the car, and in such improved car there is provided in the space occupied by the fourteen rooms of the present car, twenty-two rooms, each of which contains a single berth or bed and toilet facilities similar to those provided in the present compartment car, and with ample dressing and luggage space.

In the accompanying drawings I have illustrated two modifications of my improved car, and in said drawings

Figure 1 is a plan view showing one preferred arrangement of the compartment;

Fig. 2 is a vertical longitudinal section of the car shown in Fig. 1;

Fig. 3 is a sectional view on an enlarged scale of one compartment of the car and portions of the adjacent compartments on each side thereof, taken on line 3—3 of Fig. 2;

Fig. 4 is a transverse section on an enlarged scale on line 4—4 of Fig. 3;

Fig. 5 is a similar section showing parts of the car in different positions of adjustment; and

Fig. 6 is a plan view similar to Fig. 5 of a portion of a car wherein the number of compartments is somewhat reduced to provide a parlor or club compartment.

Referring to the drawings, 1 indicates the side walls of a Pullman car of the dimensions employed for the newer compartment cars with transversely extending rooms. In these cars the windows 2 are arranged in pairs, as shown, and an aisle 3 extends along one side of the car to give access to the compartments 4 which extend along the other side wall of the car.

In Fig. 1 I have shown twenty-two compartments numbered 1-22. Compartment No. 1 has one wall composed of sheet metal of usual construction in cars of this type extending from floor to ceiling on the side toward the platform of the car from which it is separated by a closet 6 to provide a passage between the platform and the hallway 3. Within the compartment 1 the space adjacent the wall 5 is open and extends from floor to ceiling and is preferably about two feet in width, which is the width now allowed between the wall of the compartment and the side edge of the berth or bed 7. The window 2 of compartment 1 is at the end of this free space and constitutes with the window in the closet 6, one of the spaced pair of windows extending along the side of the car. The bed 7 in compartment No. 1 is a raised, or upper, berth, and its support 8 forms part of the partition between compartment No. 1 and compartment No. 2, as more particularly shown in Fig. 2. This partition between every other two adjacent compartments consists of the support 8 for the upper berth and an upper vertical sheet metal portion 9 extending from the support 8 to the roof of the car, a middle vertical sheet metal portion 10 depending from the other edge of the support 8 and joining the corresponding edge of a support 11 for the berth 12 of compartment No. 2, and a lower sheet metal portion 13 depending from the opposite edge of the support 11 in the same plane as the part 9, the support 11 also of course forming part of the partition.

Compartment No. 2 comprises in addition to the berth space between the supports 11 and 8, an open space 14 extending the full height of the car and the same width as the

space in compartment No. 1 between the partitions 5 and 10, the window 2 for compartment 2 being located in this space and forming with the window in compartment 3 the second pair of windows on the side wall of the car. Compartment 2 is separated from the adjacent compartment 3 by a sheet metal partition 15 similar to the partition 5, which partition may, if desired, have a door 15^a whereby the two adjacent compartments may be thrown together if desired. The compartment 3 is in all respects similar to the compartment 1 and compartment 4 is similar to compartment 2, and so on, throughout the 13 length of the car.

Under each window there is provided a toilet 16 with a folding wash stand 17 above the toilet similar to the wash stand and toilet now provided in compartment cars 20 of this type, and therefore not described in detail in this application. The upper edge of the wash stand when folded against the window extends somewhat above the window sill and is shown in Fig. 5. If desired a ventilating screen may be placed in the window to occupy this lower portion thereof and conceal the wash stand from view from outside the car.

Above the wash stand there is hinged to one 30 side of the window frame a mirror 18 which serves the double purpose of providing a mirror over the wash stand when the latter is in use and at the same time closing the window at this time, which, of course is desirable. When the mirror 18 is open against the partition wall, as shown in dotted lines, it leaves the window unobstructed for view or ventilation.

To give ready access to the upper berth I 40 preferably provide folding steps 20 which are pivoted at one corner as indicated at 21 to the corner of the toilet enclosure adjacent the bottom of the lower berth as shown in Fig. 3. These steps comprise two sections, 45 the lower section of which is mounted on casters so that they may be readily swung out into the space of the compartment immediately in front of the toilet so that when the upper steps are swung into position as shown 50 in Fig. 5, the weight will be supported by the toilet and will provide a flight of easy steps to give access to the upper berth.

After the passenger mounts the steps to the upper berth the steps may be left in place 55 ready for descent in the morning, when they can be swung back under the berth out of the way, as shown.

It will be observed that in my improved car each compartment is complete in itself, 60 having a full size berth and individual toilet facilities, with clear floor space of the same area now provided, that is, a two foot width of floor space and a thirty-two inch wide berth or bed. In the present compartment 65 cars of this type each compartment thus re-

quires approximately fifty-six inches of space lengthwise of the car, whereas in my improved car I provide two complete single bed compartments in a floor space extending but seventy inches lengthwise of the car, so that in the space occupied by fourteen rooms, which is the maximum now permissible in a Pullman car of standard length, I am able to provide twenty-two separate rooms, thus closely approximating the maximum capacity 75 of an ordinary Pullman sleeper.

Instead of providing sleeping compartments for the full length of the car I may, if desired, provide a lesser number of compartments, preferably eighteen, as shown in 80 Fig. 6, with the remaining space forming a parlor or club compartment. Where eighteen rooms only are provided, as shown in Fig. 6, the parlor compartment 25 at the end of the car will be approximately fifteen and one-half feet long, which provides sufficient space for eighteen chairs, as shown, whereby a numbered seat may be sold with each room. It is preferable to provide eighteen rooms for the reason that under the present interstate commerce regulations a minimum of eighteen fares is required for each car paid for on the car basis and extra must be charged where the accommodations provided in the car are insufficient for eighteen passengers. 95

I claim:

1. In a compartment car, a plurality of separate compartments extending transversely of the car, a berth in each compartment, the berths for two adjacent compartments being arranged one above the other, one of said compartments having its free floor space on one side of said berths and the other of said compartments having its free floor space on the other side of said berths, 100 windows in the side wall of said car at the end of said free floor space, and mirrors adapted to be closed against said windows or moved away therefrom.

2. In a compartment car, a plurality of separate compartments extending transversely of the car, a berth in each compartment, the berths for two adjacent compartments being arranged one above the other, a partition dividing said compartments comprising a portion extending from one edge of the upper berth to the ceiling, a second portion extending from the opposite edge of said upper berth to the corresponding edge of the lower berth, a third section extending 110 from the lower berth to the floor, and a ladder adjustable from a position under said lower berth to a position to give access to said upper berth.

3. In a compartment car, a plurality of separate compartments extending transversely of the car, a berth in each compartment, the berths for two adjacent compartments being arranged one above the other, a partition dividing said compartments com- 115 120 125 130

prising a portion extending from one edge of the upper berth to the ceiling, a second portion extending from the opposite edge of said upper berth to the corresponding edge 5 of the lower berth, a third section extending from the lower berth to the floor, a partition extending transversely of said car and spaced from the partition section connecting said berths to provide free floor space for the 10 compartment containing the upper berth, and a ladder for giving access to said upper berth supported in the space beneath the lower berth and adapted to be shifted into the space adjacent the upper berth when desired.

4. In a railway car having a continuous floor level throughout, the combination of a longitudinal partition at one side of the center of the car providing an aisle along one

side, transverse partitions extending from 20 said longitudinal wall to the opposite side wall of the car, said partitions dividing a portion of said car into a plurality of transverse compartments, each compartment comprising a berth section formed by a horizontal offset of said partition, the berth sections of adjacent compartments being arranged one over the other, and a free floor space 25 alongside said berth section, with a door in said longitudinal wall at the end of said free floor space of each compartment, windows in 30 each compartment in the wall opposite said doors, and a lavatory in each compartment at the end of the free floor space opposite 35 said door.

In testimony whereof I affix my signature.

WOOLRIDGE B. MORTON.
